UNITED STATES PATENT OFFICE.

WINTHROP LINCOLN FAY, OF DEXTER, MAINE.

EXTENSION-GAP ENGINE-LATHE.

1,031,635.

Specification of Letters Patent.

Patented July 2, 1912.

Application filed June 19, 1911. Serial No. 634,151.

To all whom it may concern:

Be it known that I, WINTHROP LINCOLN FAY, of Dexter, in the county of Penobscot and State of Maine, have invented certain new and useful Improvements in Extension-Gap Engine-Lathes, of which the following is a specification.

My invention relates to engine lathes of the class known as "extension gap engine lathes." In these lathes the bed is mounted on the frame of the machine in such a way as to slide longitudinally whereby a gap or space may be formed adjacent to the head stock to allow full diameter of swing. Hitherto the longitudinal adjustment of the movable bed has been effected by hand operated devices which were slow in operation and required considerable effort to work.

The object of my invention is to apply to the moving of the bed the regular power of the machine so arranged that it may be applied quickly and easily. With this end in view I cut a screw thread on the regular feed rod and secure to the movable bed a sectional nut capable of being temporarily engaged with the feed rod to move it to the desired position.

I illustrate my invention in the accompanying drawing, in which—

Figure 1 is a side elevation of an extension gap engine lathe with my invention applied, only those parts of the lathe being shown which are necessary to the understanding of the invention. Fig. 2 is a part front elevation and part section of the mechanism connecting the feed rod with the movable bed somewhat modified from the form shown in Fig. 1, and Fig. 3 is a section on X X of Fig. 2.

In the drawing, like parts are marked with like letters.

In the drawing, *a* represents the main frame or foundation of the lathe, *b* is the face plate on the head-stock, *d* the tool carriage, *c* the tail-stock, *e* the movable bed, *g* the lead screw and *f* the feed rod. The gears connecting the feed rod with the lead screw are shown at *h*, *h'* and *h''* and are inclosed in a casing *i*. The gear *h* is splined to the feed rod in the usual manner. The movable bed *e* is moved longitudinally whenever required by the feed rod *f* which

is screw threaded for this purpose. A sectional nut is secured to the bed *e* in such a manner as to be readily connected to and disconnected from the feed rod. As here shown, I provide a half nut *j* preferably pivoted to the casing *i* as shown in Figs. 2 and 3 so that it may be swung up and held in engagement with the under side of the feed rod. A handle *j'* is provided by which the half nut may be manipulated.

In Fig. 1 the half nut and the bracket *j* by which it is secured to the movable bed are separated from the casing containing the connecting gears, but in Figs. 2 and 3 the bracket is formed as a part of the casing containing the gears.

The operation of my device is obvious from its construction. The nut *j* normally hangs down out of engagement with the feed rod, and when it is desired to move the bed one way or the other, the half nut is held by hand against the under side of the feed rod engaging the screw thread and moving the bed into the desired positions. When the bed has arrived at the desired position the nut is simply released and it at once drops out of engagement.

The bed may be made to move in either direction by running the lathe ahead or reversing the motion.

I claim:

1. In an extension gap engine lathe, the combination of a longitudinally movable bed, a screw threaded and slotted feed rod, and a sectional nut on said movable bed adapted to engage and disengage said feed rod.

2. In an extension gap engine lathe, the combination of a longitudinally movable bed, a screw threaded and slotted feed rod, and a half nut pivoted to said bed and adapted to engage said feed rod.

3. In an extension gap engine lathe, the combination of a longitudinally movable bed, a screw threaded and slotted feed rod, and a half nut pivoted to said bed and adapted to be swung into engagement with the under side of said feed rod.

WINTHROP LINCOLN FAY.
